CLAIM

The ornamental design for a reagent plate, as shown and described.

DESCRIPTION

FIG. 1 is a front perspective view of a reagent plate according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear bottom perspective view thereof; and,

FIG. 9 is a cross-sectional view taken along line 9-9 of FIG. 6.

The broken lines, the areas within them, and the unshaded areas surrounded by both broken lines and solid lines depict portions of the reagent plate that form no part of the claimed design.
